RELIEF VALVE CONSTRUCTION

Trent H. Holmes, Middletown, Conn., assignor
by mesne assignments to Niles-Bement-Pond
Company, Hartford, Conn., a corporation of
New Jersey

Application April 13, 1944, Serial No. 530,872

6 Claims. (Cl. 137—53)

1

This invention relates to valves and particularly to a pressure relief valve adapted primarily for fuel pumps for internal combustion engines.

An object of the invention is to improve the pressure applying device for the relief valve spring so that this valve may have an extremely slight movement away from its seat against the pressure of a light spring, this opening being sufficient to enable gases trapped within the pump to escape during the normal operation of the pump but restricting passage past the valve of any liquid such as gasoline or other liquid fuel until a predetermined pressure has been built up within the pump.

Another object of the invention is to provide means for retracting the end of the relief valve spring adjacent the relief valve so that the relief valve may be opened slightly against the pressure of a light spring prior to the pressure of the main relief valve spring being applied against further opening movement of the valve.

And finally it is an object of the invention to provide adjusting means for positioning the main pressure applying spring relatively to the valve so that the valve may have an adjustable slight relatively free movement prior to its engagement with and compression of the main pressure applying spring, the pressure of this spring being regulated in the usual manner.

With the above and other objects in view the invention includes the features of construction and operation set forth in the following specification and illustrated in the accompanying drawings.

In the accompanying drawing annexed hereto and forming a part of this specification, I have shown the invention embodied in a standard form of fuel pump for aircraft engines, but it will be understood that the invention can be otherwise embodied and that the drawing is not to be construed as defining or limiting the scope of the invention, the claims appended to this specification being relied upon for that purpose.

In the drawing the figure shows a central longitudinal section in elevation of a portion of a standard fuel pump, a relief valve and controlling mechanism therefor forming the present invention being shown in operative relation thereto.

In the above-mentioned drawing there has been shown but one embodiment of the invention which is now deemed preferable, but it is to be understood that changes and modifications may be made within the scope of the appended claims without departing from the spirit of the invention.

Briefly and in its preferred aspect, the inven-

2

tion may include the following principal parts: First, a pump, that shown in the accompanying figure being a rotating vane type fuel pump for aircraft engines, a part only of the rotating member and pump casing being shown; second, a pressure relief valve for said pump normally forced by spring pressure toward its seat; third, means to regulate the pressure exerted by said spring to force the valve toward its closed position; fourth, means to restrict the extended position of the spring adjacent the valve; and fifth, a supplemental light spring engaging and normally forcing the valve into its closed position.

Referring more in detail to the figure of the drawing, there is shown a portion of a fuel pump casing 10 of standard or conventional rotating vane type. This pump may, as is usual, have a pressure relief valve 11 of usual construction normally forced toward its seat 12 by a spring 13 and being guided by engagement of short cylindrical piston portions 14 and 14a forming parts of the relief valve and slideable within suitably bored portions of the valve casing 19. Also, if desired, the valve 11 may have a reverse acting relief valve 15 engaging the lower surface of the pressure relief valve 11 and normally spring pressed toward its closed position as shown. As this reverse acting relief valve forms no part of the present invention, no further description is thought to be necessary.

Above the upper cylindrical guiding portion 14 of the relief valve 11 is a flexible diaphragm 16 and on either side of this diaphragm are dished plates 17 and 18. The lower plate 17 directly engages the upper surface of the relief valve. The periphery of the diaphragm is clamped between surfaces of the valve casing 19 and the valve bonnet 20 so that limited movements of the valve 11, the plates 17 and 18 and the central portion of the diaphragm 16 are permitted. The diaphragm 16 may be, as usual, of rubber or composition having some of the qualities of rubber permitting flexure when the valve is moved from open to closed position while maintaining a pressure tight joint. Above the upper plate 18 is the main relief pressure applying spring 13. The lower end of this spring 13 fits within the flange of a cap member 22, the edges of which are closely adjacent or may bear against the upper diaphragm plate 18. The upper end of the pressure applying spring 13 may be adjusted by rotation of an adjusting screw 23 which may be retained in any adjusted position by a flange formed thereon being clamped by a collar 24 threaded upon the outer or upper end of the valve bonnet 20. By rotation of the threaded member 23 the position

of the upper end of the spring 13 may be widely varied to vary the pressure at which the relief valve may open. The upper end of spring 13 bears against a retainer 32 which threadedly engages the screw 23. The retainer 32 is held against rotation by lug 33 which engages in slot 34 in bonnet 20 so that rotation of member 23 produces vertical movement of retainer 32, thereby varying the loading of spring 13.

To determine and limit the extended position of the lower end of the pressure applying spring 13 so that the valve 11 may have free but extremely limited movement from its seat prior to compression of the spring 13, the cap member 22 against which the lower end of the spring bears is held in any adjusted position by a vertically disposed screw 25. The head of the screw 25 at its lower end engages against the under side of the bearing or cap member 22. The cap member 22 and spring 13 can therefore move upward but their lowermost position is governed by the vertical adjustment of the cap member 22 which is controlled by the position of the head of screw 25. As will be seen in the figure, the rod or screw 25 extends centrally through the nut 23. To raise and lower this threaded rod 25 to vary the position of the cap member 22 to limit the position of the lower end of spring 13, the rod 25 at its upper end has threaded thereon a nut 26 centrally disposed above the nut 23 for adjusting the pressure of spring 13. Preferably there is a spring washer 27 between these nuts 23 and 26 and a second spring washer 28 above the nut 26 and below a cap nut 29 extending over the upper end of the threaded rod 25. Disposed between the cap member 22 and the upper diaphragm plate 18 is a light spring 30. With the cap member 22 in its lowermost position as shown in the figure, the valve 11 is held in contact with its seat by the spring 30.

In adjusting this relief valve 11 the pressure of spring 13 at which the relief valve may open in the usual manner is regulated by adjustment of the threaded nut 23 by means of which the upper end of the spring 13 is raised or lowered. While this adjustment is being effected the head of threaded rod 25 is in a position low enough to permit the full pressure of the spring 13 to act against the relief valve 11 and hold it firmly against its seat 12. The rod 25 is then raised slightly by rotation of its nut 26 until the cap or bearing member 22 for the lower end of the spring 13 just releases its pressure from the upper diaphragm plate 18 to permit vapors entrapped within the discharge side of the pump to escape past the relief valve 11. The opening, however, will not be sufficient to permit passage of any liquid past the valve 11 until the pressure retaining the valve 11 against its seat 12 is overcome and the relief valve 11 opened against the pressure of this spring 13. During normal operation of the pump with the valve 11 held toward its seat 12 by spring 13 a light spring 30 holds the valve 11 tightly closed but permits slight movement upward of the valve 11 without compression of spring 13 and during normal operation of the pump. As soon as a predetermined pressure within the discharge side of the pump is reached, the spring 13 is compressed in the usual manner and the valve 11 opens.

What I claim is:

1. Relief valve mechanism comprising a casing having a valve seat therein, a valve means within said casing cooperating with said seat, a first spring retainer, means operable from the

exterior of said casing for adjusting the position of said retainer with respect to said casing, means for locking said retainer in any adjusted position, a second spring retainer, an abutting connection between said second retainer and said valve means, a first spring held in compression between said retainers and effective to bias said second retainer in a direction to operatively engage said valve means and move it toward closed position, a second spring retained between said second retainer and said valve means and biasing said valve means toward closed position, means for limiting the movement of said second retainer toward said valve means so that when said valve means is in a range of positions near its closed position only said second spring is effective to bias said valve means, means operable from the exterior of said casing independently of the adjustment of said first retainer adjusting means, for adjusting the position of said limiting means, and means for locking said limiting means in any adjusted position.

2. Relief valve mechanism comprising a casing having a valve seat therein, a valve within said casing cooperating with said seat, a plurality of pistons on opposite sides of said valve, reciprocable in bores in said casing, for guiding said valve, a spring for biasing said valve toward said seat, stop means for limiting the movement of said spring toward said valve seat to permit said valve to move a predetermined distance from said seat without opposition by said spring, means movable from the exterior of said casing for adjusting the loading of said spring, and means movable from the exterior of said casing independently of the adjustment of the first movable means for adjusting the position of said stop means to vary said distance.

3. Relief valve mechanism comprising a casing having a valve seat therein, a valve within said casing cooperating with said seat, said casing having a bore aligned with said valve and extending thru said casing to the exterior thereof; a spring located in said bore for biasing said valve toward said seat; a retainer for the outer end of said spring slidably longitudinally in said bore but non-rotatably mounted therein; an adjustment member in said bore having a nut portion outside said casing to facilitate rotation thereof, a flange portion adjacent said nut portion of greater diameter than said bore so that the edge of said flange portion engages said casing around said bore, and a portion projecting into said bore and threadedly engaging said retainer so that rotation of said adjustment member causes longitudinal movement of said retainer; a lock nut threadedly engaging said casing around said adjustment member and having a portion overlying said flange portion so as to engage said flange portion and lock said member against rotation when said nut is tightened; said adjustment member having a bore extending longitudinally thru its center; a retainer for the inner end of said spring having a central aperture; a stop member having a stem portion extending thru said bore in said adjustment member and thru said aperture, an enlarged head portion engaging the inner face of said inner retainer to limit the inward movement thereof so as to permit said valve to move a predetermined distance from said seat without opposition by said spring, and a threaded portion extending outwardly of said casing beyond said adjustment member; and nut means on said threaded portion of said stop member for adjusting the

position of said inner retainer and thereby varying said distance.

4. A relief valve mechanism according to claim 2 including a second spring between said stop and said valve, the loading of said second spring being relatively much lighter than the loading of the first spring, so as to permit said valve to open only enough to pass vapors thru said valve, but not enough to pass liquids therethru.

5. Relief valve mechanism according to claim 1, including a flexible sealing diaphragm attached to said valve and said casing.

6. Relief valve mechanism according to claim 2, including a flexible sealing diaphragm attached to said valve and said casing.
